(57) **CLAIM**

The ornamental design for an overcap, as shown and described.

DESCRIPTION

FIG. 1 is a front top perspective view of an overcap, showing our new design;

FIG. 2 is a front bottom perspective view of the overcap of FIG. 1;

FIG. 3 is a rear top perspective view of the overcap of FIG. 1;

FIG. 4 is a rear bottom perspective view of the overcap of FIG. 1;

FIG. 5 is a front view of the overcap of FIG. 1;

FIG. 6 is a rear view of the overcap of FIG. 1;

FIG. 7 is a right side view of the overcap of FIG. 1;

FIG. 8 is a left side view of the overcap of FIG. 1;

FIG. 9 is a top view of the overcap of FIG. 1;

FIG. 10 is a bottom view of the overcap of FIG. 1;

FIG. 11 is a first perspective view of the overcap of FIG. 1 disposed on a bottle; and,

FIG. 12 is a second perspective view of the overcap of FIG. 1 disposed on a bottle.

The broken lines are shown for the purpose of illustrating both parts of the article as well as environmental subject matter of an exemplary container. None of the broken lines form part of the claimed design. The dot-dash broken lines represent the boundaries of the claim and form no part thereof.

1 Claim, 9 Drawing Sheets
